UNITED STATES PATENT OFFICE

FRANK F. BURTON, OF MOUNT CARMEL, CONNECTICUT, ASSIGNEE TO WINCHESTER REPEATING ARMS COMPANY, OF NEW HAVEN, CONNECTICUT, A CORPORATION OF DELAWARE

LOCKING-BOLT LATCH FOR BREAKDOWN FIREARMS

Application filed December 3, 1929. Serial No. 411,236.

This invention relates to improvement in locking-bolt latches for breakdown firearms and has for its main object the provision of a simple, convenient and reliable, manually-operable latch for releasably holding the barrel-locking bolt in its retired position when the same is moved thereinto to permit the barrel-unit to swing into its broken-down position with respect to the frame-unit.

With the foregoing and other objects in view, my invention consists in a spring-pressed locking-bolt latch for breakdown firearms characterized by having a portion thereof conveniently exposed for manual retirement through a portion of the frame-unit in which it is mounted.

My invention further consists in a locking-bolt latch for breakdown firearms characterized as above and having certain details of construction and arrangement of parts as will be hereinafter described and particularly recited in the claims.

In the accompanying drawings:

Fig. 1 is a broken view, partly in side elevation and partly in central longitudinal section, of a double-barreled breakdown shotgun equipped with my improved locking-bolt latch;

Fig. 2 is a corresponding view with the barrel-unit shown in its broken-down position;

Fig. 3 is a broken view in transverse horizontal section, taken on the line 3-3 of Fig. 1;

Fig. 4 is a vertical transverse sectional view taken on the line 4-4 of Fig. 2;

Fig. 5 is an enlarged-scale detached perspective view of the locking-bolt latch;

Fig. 6 is a side view of the barrel-locking bolt; and

Fig. 7 is an underside view of the same.

The embodiment of my invention herein chosen for illustration is, as shown, installed in a double-barreled breakdown shotgun, though it is obvious that the use of my invention is not so limited, since it may be advantageously employed in connection with other types of breakdown firearms.

The shotgun shown comprises the usual frame-body 10 formed at its bottom edge

with a forward extension 11 which in turn is formed with a longitudinal vertically-arranged slot or passage 12 open at its upper end and closed at its bottom end by the forward end of a trigger-plate 13 having a trigger-guard 14 within the looped form of which a pair of triggers 15 are located. The frame 10, as is usual in firearm construction, is secured to the forward end of a butt-stock 16 in any approved manner.

To provide for pivoting the barrel-unit which comprises in the main a pair of barrels 17 (only one of which appears in the drawings) and a fore end 18, as well as other incidental features, I provide a transverse trunnion-pin 19 commonly referred to as a "joint pin" and extending across the slot 12 in the extension 11 of the frame-body 10 in the opposite side-walls of which it is supported in the usual manner. This trunnion-pin is partly embedded, so to speak, in the forward wall of the slot 12 but in its central part it has the major portion of its circumference rearwardly exposed within the forward end of the said slot, as clearly shown in Figs. 1 and 2 of the drawings.

The barrel-unit is provided in its underside with a longitudinally-arranged depending lug 20 adapted to fit within the slot 12 of the frame-body 10, as clearly shown in Fig. 1 of the drawings. The forward end of the lug 20 is formed with a forwardly-facing substantially-semicircular transverse notch 21 adapted to rock upon the trunnion-pin 19 before referred to.

The lower forward corner of the extension 11 of the frame 10 is rounded off as at 22 concentrically with the trunnion-pin 19 so that the shoe 23 of the fore end 18 will snugly fit against the frame-body 10 in all positions of the barrel-unit in the swinging movement of the same with respect to the frame-body; the rear face of the said shoe being formed, as shown, with a cylindrically-contoured concave surface 24 conforming to the curvature of the surface 22 of the extension 11 and resulting in the formation of a relatively-sharp toe 25.

For the purpose of limiting the breakdown movement of the barrel-unit with respect to the frame-body 10, I employ a float-

ing barrel-stop-bar 26 mounted for vertical movement in a transverse slot 27 in the lug 20 before referred to and adapted to have its opposite ends engage with suitable abutments 5 in the side walls of the slot 12 in the extension 11.

The rear end-wall of the lug 20 is formed with a notch 28, the inclined bottom-wall 29 of which is adapted to be engaged by the 10 similarly-inclined underface 30 of the locking-nose 31 of a reciprocating barrel-locking bolt 32 mounted for movement in a horizontal bore 33 formed in the frame-body 10 and having its forward end intersecting the rear 15 end of the vertical slot 12 before referred to.

The main portion of the locking-bolt 32 is of cylindrical form and is provided at its rear end with a horizontal laterally-offsetting lug 34 formed in its outer end with a coupling- 20 notch 35 for the reception of a cylindrically-contoured operating-finger 36 depending from the underface of a substantially-disk-like operating-head 37 having a square axial bore 38 for the reception of the squared 25 lower end of the vertical shank 39 of a finger-lever 40 to which it is secured by a diametrical pin 41.

The finger-lever 40 extends rearward from the shank 39 and is located, as is usual in 30 breakdown shotgun construction, upon the upper face of the frame-body 10 and normally extends rearward over the upper face of the butt-stock 16, as clearly shown in Fig. 1 of the drawings.

For the purpose of normally urging the operating-head 37, together with the shank 39 and finger-lever 40, in a clockwise direction, as viewed in Fig. 3, and hence urging the nose 31 of the locking-bolt 32 into the 40 notch 28 of the lug 20, I employ a plunger 42 reciprocating in a rearwardly-opening socket 43 formed in the frame-body 10 (Fig. 3) and having a rearwardly-extending thrust-nose 44 of reduced diameter engaging 45 a radial thrust-face 45 upon the operating-head 37. The forward end of the plunger 42 is formed with an axial stem 46 which is encircled by a helical spring 47 bearing at its rear end against the forward end of the 50 said plunger and at its forward end bearing against the bottom wall 48 of the socket 43 before referred to.

From the foregoing it will be seen that the locking-bolt 32 is constantly urged into 55 its forwardly-extended position by the spring 47 and that it may be retracted therefrom against the tension of the said spring by a swinging movement of the finger-lever 40 in the manner well known in the art of 60 break-down firearms.

The forward face of the locking-nose 31 of the locking-bolt 32 is rearwardly and upwardly sloped to form a cam-surface 49 adapted to be engaged by a complementary 65 cam-surface 50 formed at the lower rear cor-

ner of the lug 20 of the barrel-unit for the purpose of automatically retiring the said bolt, should it, perchance, be in its projected position when the barrel-unit is swung downward from the position in which it is shown in Fig. 2 to that in which it is shown in Fig. 1. 10

To releasably hold the locking-bolt 32 in its retracted position (Fig. 2) so as to minimize the effort required to swing the barrel-unit into its locked position, I employ a locking-bolt latch 51 formed with a vertically-extending stem 52 and a horizontal forwardly-extending tripping-finger 53 and adapted at its rear upper corner to engage a latching-shoulder 54 formed in the underface of 15 the locking-bolt 32. 20

The latch 51 is adapted to reciprocate vertically in a passage 55 formed in the underface of the frame-body 10 and intersecting at its forward end the slot 12 in the extension 25 11 thereof, as shown in Figs. 1 and 2 of the drawings. The upstanding stem 52 of the latch 51 passes upward through a longitudinal clearance-slot 56 extending diametrically through the locking-bolt 32 and bears 30 at its upper end in a vertical passage 57 having its upper end opening upwardly and forwardly into a substantially-vertical finger-clearance notch 58 formed in the standing-breach 59 of the frame-body 10 adjacent the 35 junction thereof with the horizontal so-called "table" 60 constituting the upper face of the forward extension 11. 40

It will be seen that the opening of the upper end of the vertical passage 57 into the finger-clearance notch 58 exposes the upper end of the stem 52 of the latch 51 so that the same may be manually pushed downward into its releasing position against the tension of a helical spring 61 which is mainly housed 100 within an axial bore 62 extending vertically through the said latch and partway into the stem 52 thereof. The upper end of the spring 61 seats against the upper end of the axial bore 62, while its lower end is seated in a shallow upwardly-opening pocket 63 formed in the upper face of the trigger-plate 13. 105

The upward movement of the latch 51 under the urge of its spring 61 is limited by a transverse stop-pin 64 extending transversely across the frame-body 10 and over the forwardly-projecting tripping-finger 53 of the said latch. 115

For the clearance of the locking-bolt latch 51 when the same is depressed either manually or automatically, as will hereinafter appear, to disengage its rear upper corner from the latching-shoulder 54 of the locking-bolt 32, I form the latter in its underface with a clearance-notch 65. 120

In the operation of the breakdown shotgun herein chosen for the illustration of my invention, the user, when desiring to load the piece, swings the finger-lever 40 to the right with the effect, through the intermedi- 125 130

ary of the parts 39, 37, 36, 35, and 34, of re-tracting the barrel-locking bolt 32 a distance sufficient to disengage its nose 31 from the notch 28 of the lug 20, thereby permitting 5 the barrel-unit to be swung into its broken-down position, as shown in Fig. 2.

When the bolt 32 is retracted as just above described, the latching-shoulder 54 thereof is also moved rearward sufficiently to permit the 10 latch 51 to move upward under the urge of its spring 61 and effectually hold the said bolt in its retracted position when the manual pressure upon the finger-lever 40 is relaxed. Thus, not only is the barrel-locking bolt 32 15 latched in its retracted position but the finger-lever 40 is also held in its turned position into which it has just been turned to effect the "break-down" of the gun.

After loading the piece, the user swings the 20 barrel-unit into line with the frame-unit in the usual manner and as the said barrel-unit approaches its "home" position, the upper wall 66 of a shallow notch formed in the rear lower corner of the lug 20 will engage the upper 25 face of the trip-finger 53 of the latch 51 and depress the same against the tension of its spring 61, so as to disengage it from the latching-shoulder 54 in the bolt 32, with the effect of releasing the said bolt so that it may be projected forward by the spring 47 into the 30 notch 28 of the lug 20 to lock the barrel-unit, and also with the effect of returning the finger-lever 40 to its normal position in line with the longitudinal axis of the gun.

In the event that the user of the gun wishes 35 to separate the barrel-unit from the frame-unit for the purpose of conveniently packing the taken-down gun in a case for transportation or storage, the finger-lever 40 would 40 upon such separation be held by the latch 51 in its laterally-turned position, since it is first necessary to unlock the barrel-unit as above described before the same can be separated from the frame-unit.

The retention of the finger-lever 40 in its laterally-turned position not only exposes it 45 to injury during transportation but interferes to a large degree to the insertion of the frame-unit into a case. It is desirable, therefore, that the said finger-lever be returned 50 into its normal position after the separation of the two units and it is for this purpose that the upper end of the stem 52 of the latch 51 is exposed for manual depression in the finger-clearance notch 58.

After the separation of the units, the user 55 may readily insert a thumb-nail or any other instrumentality into the notch 58 and depress the latch 51 with the effect of permitting the spring 47 to swing the finger-lever 40 back into its normal position and incidentally at the same time permit the locking-bolt 32 to be projected forward until checked by the engagement of the rear end 67 of the clearance-notch 65 with the rear face of the latch 51.

Upon reassembling the two units for further use of the gun, the first downward-swinging movement of the barrel-unit will cause the cam-surface 50 of the lug 20 to engage the cam-surface 49 of the bolt 32 so as to forcibly 70 retire the latter and permit the said barrel-unit to be swung completely into its "home" position. Thereafter upon each unlocking of the barrel-unit the locking-bolt 32 will be latched in its retired position as before described. 75

I claim:

1. In a breakdown firearm, the combination with the relatively-pivoted frame-unit and barrel-unit thereof; of a barrel-locking bolt carried by the said frame-unit in position to engage a portion of the said barrel-unit to lock the same in place and formed with a transverse passage; and an automatically-releasable spring-pressed locking-bolt latch 85 co-acting with the said barrel-locking bolt to hold the same in its retracted position and having a portion extending through the passage in the said bolt and exposed through a portion of the said frame-unit for manual 90 release.

2. In a breakdown firearm, the combination with the relatively-pivoted frame-unit and barrel-unit thereof; of a barrel-locking bolt carried by the said frame-unit in position 95 to engage a portion of the said barrel-unit to lock the same in place and formed with an elongated transverse passage; and an automatically-releasable spring-pressed locking-bolt latch co-acting with the said barrel-locking bolt to hold the same in its retracted position and having a portion extending through the elongated passage in the said bolt and exposed for manual release through the 100 said frame-unit adjacent the junction of the table and standing-breech thereof.

3. In a breakdown firearm, the combination with the relatively-pivoted frame-unit and barrel-unit thereof; of a barrel-locking bolt carried by the said frame-unit in position to engage a portion of the said barrel-unit to lock the same in place and formed with a transverse passage; and an automatically-releasable spring-pressed locking-bolt latch co-acting 110 with the said barrel-locking bolt to hold the same in its retracted position and comprising a stem and a tripping-finger, the said stem extending through the transverse passage in the said bolt and exposed through a portion of the said frame-unit for manual 115 release, and the said tripping-finger extending into the path of a portion of the said barrel-unit for engagement thereby.

4. In a breakdown firearm, the combination with the relatively-pivoted frame-unit and barrel-unit thereof; of a barrel-locking bolt carried by the said frame-unit in position to engage a portion of the said barrel-unit to lock the same in place and formed 120 with a transverse passage; and an auto- 125

matically-releasable spring-pressed locking-bolt latch co-acting with the said barrel-locking bolt to hold the same in its retracted position and comprising a stem and a tripping-finger, the said stem extending through the transverse passage in the said bolt and exposed for manual release through the said frame-unit adjacent the junction of the table and standing-breech thereof, and the said tripping-finger extending into the path of a portion of the said barrel-unit for engagement thereby.

5. In a breakdown firearm, the combination with the relatively-pivoted frame-unit and barrel-unit thereof; of a reciprocating barrel-locking bolt formed with an elongated diametrical passage and carried by the said frame-unit in position to engage a portion of the said barrel-unit to lock the same in place; and an automatically-releasable spring-pressed locking-bolt latch co-acting with the said reciprocating barrel-locking bolt to hold the same in its retracted position and comprising a vertical stem and a horizontally-offsetting tripping-finger, the said vertical stem extending upward through the diametrical passage in the said reciprocating bolt and exposed through a portion of the frame-unit for manual release and the said horizontally-offsetting tripping-finger extending forwardly into the path of a portion of the said barrel-unit for engagement thereby.

6. In a breakdown firearm, the combination with the relatively-pivoted frame-body and barrel-unit thereof; of a finger-clearance notch formed in the standing-breech of the said frame-body; a barrel-locking bolt carried by the said frame-body in position to engage a portion of the said barrel-unit to lock the same in place and formed with a transverse passage; and an automatically-releasable spring-pressed locking-bolt latch comprising a vertical stem and a horizontal forwardly-offsetting tripping-finger, the said stem extending upward through the transverse passage in the said locking-bolt and into the said finger-clearance groove in the said standing-breech for manual release, the said tripping-finger extending into the path of a portion of the said barrel-unit for engagement thereby.

In testimony whereof, I have signed this specification.

FRANK F. BURTON.
